AIR CONDITIONING APPARATUS

Charles L. Bryant, Cleveland, Ohio, assignor to
 C. L. Bryant Corporation, Cleveland, Ohio, a
 corporation of Ohio

Application June 26, 1937, Serial No. 150,597

9 Claims. (Cl. 126—116)

This invention relates to air conditioning apparatus, and the object of this invention is to provide new and improved apparatus of this type.

In the drawings accompanying this specification and forming a part of this application, I have shown, for purposes of illustration, one form which my invention may assume, and in these drawings:

Figure 1 is a vertical sectional view through the apparatus, certain parts being shown in elevation and certain parts being broken away.

Figure 2 is a front elevational view of the embodiment shown in Figure 1, parts being broken away.

Figure 3 is an enlarged fragmentary sectional view corresponding substantially to the line 3—3 of Figure 1.

Figure 4 is an enlarged broken vertical sectional view corresponding substantially to the line 4—4 of Figure 2.

Figure 5 is a transverse sectional view corresponding substantially to the line 5—5 of Figure 4.

Figure 6 is a fragmentary vertical sectional view corresponding substantially to the line 6—6 of Figure 5.

Figure 7 is a transverse sectional view corresponding to the line 7—7 of Figure 4, parts being broken away to better accommodate the view to the sheet.

Figure 8 is a fragmentary enlarged sectional view corresponding substantially to the line 8—8 of Figure 5.

Figure 9 is a fragmentary sectional view corresponding to the line 9—9 of Figure 1, parts being omitted for the sake of clearness.

Figure 10 is a fragmentary vertical sectional view showing, in enlarged relation, the upper portion of the apparatus shown in Figure 1, some parts being shown in elevation.

Figure 11 is a sectional view corresponding generally to the line 11—11 of Figure 10, and

Figure 12 is an enlarged fragmentary sectional view of a detail.

Referring to the drawings, the apparatus includes an outer casing 15 and an inner casing 16, the outer casing being more or less of an ornamental nature, and in some instances this casing may be omitted. The outer casing is provided with a removable panel 17, providing access to the interior of the casing, and this panel may be quickly attachable to and detachable from the casing by means of a catch device 18. As best shown in Figure 5 the outer casing 15 is transversely spaced from the inner casing 16,

the spacing at the side carrying the panel 17 being considerably greater than the spacing at the remaining sides, and this greater spacing provides a compartment 19 for housing mechanism hereinafter referred to.

As shown in Figures 1 and 2, the outer chamber 15 rests on a base 20 comprising a rectangular member 21, formed of bar iron, and strengthened by a plurality of cross-bars 22. Disposed upon the cross-bars 22 is a supporting plate 23, 10 formed of any suitable material. Means are provided to effect leveling of the base, these means, in this instance, comprising a bolt 21a (see Figures 1, 2, and 12) positioned at spaced parts of the base 20, preferably at the corners of the 15 base, these bolts 21a screw-threadedly taking through apertures formed in a horizontal portion of the member 21, and the end of the bolt being engageable with the supporting surface. Thus, it will be apparent that if the supporting 20 surface is uneven, the bolts 21a may be adjusted so as to bring the base 20 to a desired position.

As suggested in Figure 4, the outer casing 15, adjacent its upper end, has a detachable connection with the upper end of the inner casing 16, 25 this connection also receiving the lower open end of a casing structure 24 forming at least part of a bonnet chamber 24a. This casing structure 24 may be of various lengths, to suit the needs of risers 25 leading from the bonnet chamber 24a 30 to receiving means, such as rooms, spaced from the apparatus.

The inner casing 16 closely encompasses a chamber member 26, having a top wall 27, a bottom wall 28, a front wall 29, a rear wall 30, and 35 side walls 31. As best shown in Figures 5 and 7, the front and rear walls 29 and 30 respectively, and the side walls 31 are corrugated, so as to provide recesses or furrows on the inner surfaces of these walls, and recesses or furrows on the 40 outer surfaces of these walls, the inner and outer recesses being complementary. Referring to Figure 7, it will be noted that the inner and outer furrows 32 and 33 of the side walls 31, are deeper than the inner and outer furrows 34 and 35 of 45 the front and rear walls 29 and 30.

The inner casing 16 circumscribes the outer crests formed by the corrugated walls, a plurality of spacing members 36, such as spaced wires secured to either the chamber 26 or the interior 50 of the inner casing 16, serve to space the inner casing 16 from the chamber 26. At the forward lower end of the chamber 26 an opening 37 is formed, defined by a lateral rectangular extension 38 of the front wall 29, this extension 55

being of a width substantially equal to the width of the corrugated portion of the front wall 29, and having its lower wall formed by an extension of the bottom wall 28 of the chamber 26. The 5 corrugations in the front wall 29 are longitudinally interrupted to provide a space 39 above the lateral extension 38. The top wall 27 closes the upper end of the corrugations in the front wall 29, and an inwardly extending wall 40 serves to close the 10 lower end of these corrugations, and also cooperates with the top of the lateral rectangular extension to define the space 39.

The corrugated walls of the chamber 26 do not extend into the corners of the inner casing 16, 15 thus forming elongated pockets adjacent these corners, and these pockets are partially blocked up by tubular members 41 and 43, the members being formed with closed ends. As shown in Figures 1, 7, and 9, the tubular members 41 adjacent the front wall 29 extend from the upper wall 27 of the chamber 26 to a point substantially in line with the wall 40 defining the lower end of the corrugations of the front wall 29. The tubular members 41 fit against the adjacent walls 25 of the inner casing, but are spaced from the adjacent surfaces of the front and side walls 29 and 31 respectively, to provide elongated passageways 42, as seen in Figure 7. Tubular members 43, similar to the members 41, are positioned adjacent the rear wall 30 of the chamber 26, but in this case the members 43 extend from the top wall 27 of the chamber 26 to the bottom wall 28, and these members are spaced from the adjacent surfaces of the rear wall 30 and the side walls 35 31 to provide elongated passageways 44. In the particular construction illustrated, the chamber 26 has its front, rear, and side walls, formed of sheet-metal and as separate units, these walls being joined by welded connections as shown at 40 45 in Figures 5 and 7. The top and bottom walls 27 and 28 may also be formed separately and welded to the other walls. Of course the chamber 26 may be formed in any other suitable manner, as will be obvious.

45 The bottom wall 28 of the chamber 26, and the lower marginal surfaces of the inner casing 16 rest upon a flange 46 partially formed around an opening 47 in a generally rectangular receptacle 48, the front wall of the receptacle being inclined as shown at 49 and notched to receive the extension 38. The rear wall of the receptacle is provided with a flanged aperture 50, adapted to receive the outlet end 51 of a blower mechanism 52. The blower mechanism 52 comprises a casing 55 formed with an axial inlet, and the casing has a fan disposed therein, the fan being driven through a suitable driving connection with an electric motor 53. The blower mechanism 52 is secured to the base 23 by means of upright strips 54 and horizontal strips 55, respectively secured to the blower mechanism 52 and the cross-bars 22. The blower mechanism 52 is disposed within a casing 56, supported on the base 23, and secured to the rear wall of the outer casing 15, and has an inlet duct 57, and air filtering means 58, interposed between the inlet duct 57 and the inlet of the blower mechanism 52.

70 The top wall 27 of the chamber 26 is apertured as shown at 59, and a flue pipe 60 is secured to the top wall 27 in any suitable manner, such as welding or the like, this flue pipe having an opening 61 in line with the opening 59, the flue pipe 60 leading outwardly from the inner casing 15 and outer casing 16 to within a draft hood 62, and 75 a pipe 63 leading from the draft hood to a suitable

exhaust, such as a chimney (not shown). It will be apparent that the inner furrows 32 of the side walls 31, and the inner furrows 34 of the front and rear walls 29 and 30, form paths leading generally from the bottom of the chamber 26 to the exhaust aperture 59.

The opening 37 formed by the lateral rectangular extension 38 of the chamber 26 is closed by a plate 64 having a marginal flange 65 circumscribing the opening 37 of the lateral extension 10 38. The plate 64 is preferably made in upper and lower halves 66 and 67 respectively, and the halves have an overlapping joint 68 held together by a bolt connection 69. Adjacent the upper end 66 of the plate 64 a door 70 is provided, 15 hinged to the plate 64 as shown at 71, and provided with an inspection window 72. The lower half 67 of the plate 64 is formed with means providing a pair of vestibules 73 and 74, each vestibule communicating with the interior of the 20 chamber 26. The vestibule 73 has a lower open side 75 closed by a door 76, and the vestibule 74 has a lower open side 77 closed by a door 78. The doors 76 and 78 may be integrally connected with a strip 79, here shown to be of T-cross-section 25 for strengthening purposes, and each door carries a hinge part adapted to be pivotally connected to a hinge part carried by the plate 64, as shown at 80.

A burner construction 81 is carried by the lower 30 wall 28 of the chamber 26, this construction being substantially similar to the construction shown in my co-pending application, Serial Number 74,929, filed April 17, 1936, and only a brief description of this construction is believed to be necessary. 35 The burner construction 81 comprises a manifold device 82 having a central trough-shaped channel 83 communicating with a conduit 84 leading from a source of fuel supply. The walls of the trough 83 define shallow troughs 85 and 86 upon 40 either side of the trough 83, these troughs 85 and 86 extending the length of the manifold device 82, as suggested in Figure 4. Communicating with the trough 85 is a pair of mixing chambers 87, and communicating with the trough 86 is a 45 pair of mixing chambers 88. The mixing chambers 87 respectively connect to burners 90, and the chambers 88 respectively connect to burners 91. The burners 90 and 91 are provided with feet 92 and 93 respectively, which rest on the 50 lower wall 28 of the chamber 26. Supported by the burners 90 and 91 are chambered baffle means 94 and 95 respectively, each having an angular part 96, forming a support for a plate 97, the plate 97 at its forward end is extended as shown 55 at 98 to fit within the opening 37 defined by the lateral extension 38, and the forward surface of the plate 97 abuts the plate 64, and rests on a flange 99 secured to the plate 64. The plate 97 also has a downwardly extending back part 100 60 cooperating with the feet 92 and 93 to form a generally rectangular compartment at the lower part of the chamber 26.

The pipe 84 extends outwardly from the compartment formed by the plate 97 and feet 92 and 65 93, through an aperture in the plate 64, and is connected to a manual shut-off valve 101. The valve 101 is in turn connected to the outlet chamber 102 of a valve 103, the inlet chamber 104 of this valve being connected to a pipe 105 leading 70 to a pressure regulator 106. The pressure regulator 106 may be of the type wherein a valve is connected to a diaphragm within the diaphragm chamber 107, the lower side of the diaphragm 75 communicating directly with the fuel pressure 75

in a pipe 108 leading to a source of supply, and the upper side of the diaphragm communicates with the atmosphere through a conduit 109.

The entire burner assembly 81, together with the valves and pipe connections may be assembled on the lower section 67 of the plate 64, and this assembly may be moved to proper position within the lower interior of the chamber 26, and then the lower section 67 may be secured to the upper section 66, by means of the bolts 69. The plate 64 may be secured to the lateral extension 38 in any suitable manner, as by means of bolts not shown.

Opening and closing of the valve 103 may be electrically controlled by a motor device 110 connected to the stem 111 of the valve member within the valve 103, movement of the motor device 110 not only effecting movement of the valve stem 111, but simultaneously effecting movement of a lever 112 extending outwardly from the casing of the motor device 110. The lever 112 is connected to a lug 113, formed on the door 76, by means of a chain 114, a spring 115 being interposed in the length of chain so as to prevent straining of the chain. The lug 113 is provided with a plurality of openings for receiving the lower end of the chain 114, the opening to be chosen being dependent upon the input requirement of the apparatus.

The burner construction 81, in this particular instance, uses gas as a fuel, although it will be evident that the burner construction may be such as to use other types of fuel.

When the motor device 110 moves to open up communication between the ports 102 and 104 of the valve 103, this movement also lowers the lever 112 so as to open the doors 76 and 78, thereby uncovering the openings 75 and 77 of the vestibules 73 and 74, so that primary air is directed to the mixing chambers 87 and 88 and secondary air is directed to the lower ends of the chambered baffles 94, 95. On the other hand, when the motor device 110 moves to close communication between the ports 102 and 104 of the valve 103, this movement raises the arm 112 so as to move the doors 76 and 78 to closed position, thereby cutting off the supply of air to the burner mechanism. In event that the chain 114 should break for any reason, the doors 76 and 78 will fall to open position under the influence of gravity, so that if the valve 103 is opened, an accumulation of raw gas is prevented from filling the chamber 26.

Pilot burners 116 and 117 are provided for each pair of burners 90 and 91, these pilots being carried by supporting blocks 118 which are attached to the respective feet 92 and 93. The pilot burners have connection with a conduit 119, in turn connected by a T-connection with a pipe 120 leading from the inlet port 104 of the valve 103. A hand cock 121 may be interposed in the pipe line 120 to manually control the flow of fuel to the pilot burners 116 and 117. Carried by one of the supporting blocks 118 is a tube 122, this tube being connected to the tube 109 leading from the upper side of the diaphragm chamber 107 of the regulator valve 106, and the purpose being that in event the diaphragm should spring a leak, fuel from the diaphragm chamber will pass along the tube 109 and vent through the tube 122 to a point adjacent the pilot flame, so that this escaping fuel will be consumed.

Carried by each of the connecting blocks 118 is a thermally responsive device 123 leading to a control device 124. As best shown in Figure 8, a

thermally responsive device 123 is positioned adjacent a small aperture in the respective pilot burner, in the case of Figure 8, the device is positioned adjacent an aperture 117a formed at an intermediate portion of the pilot burner 117, and a flame from the aperture 117a plays on the thermally responsive device 123 when the pilot burner 117 is burning. One form which the thermally responsive device 123 and control device 124 may take is suggested in Figure 8, and as shown, the responsive device 123 houses a thermo-electric junction 125 leading to a magnet 126 within the control device 124. When a flame is burning at the aperture 117a, a small current will be generated within the thermal responsive device 123 to energize the magnet 126, so that a plate 127 will be drawn to the poles of a magnet against the action of a spring 128. Should the flame at the aperture 117a be extinguished, the spring 128 will urge the plate 127 away from the magnet 126, and cause a bridge 129 to engage the contacts 130. The electrical connection of the contacts 130 with the motor device 110 is such, that when the bridge engages the contacts 130, the motor device will move to close communication between the ports 102 and 104 of the valve 103, and also move the doors 76 and 78 to closed position. A reset button 131 is provided for effecting proper relation of the fuel control system. Inasmuch as two pilot burners are used in this construction, two control devices 124 are shown for operation with respective pilot burners, and as a matter of convenience, these control devices are carried on the upper surface of the vestibule 74 by means of machine screws, the vestibule 74 being provided with a pair of apertures 132, one of which is shown in Figure 8, for the passage of a conduit 133 leading to the thermal responsive devices 123.

A connection 134 (Figures 1 and 3) in the pipe 105 may screw-threadedly engage the top of a foot 135, so that most of the weight of the fuel conduits and control devices is carried by this foot.

Within the chamber 26 and adjacent the top wall 27 thereof is a baffle plate 136, supported in position by means of rods 137, the lower end of each rod having nuts 138 clamped on opposite sides of the baffle plate 136, and the upper end of each rod passing through an aperture in a strip 139, the extremity of the upper end screw-threadedly receiving a nut 139a. As best shown in Figures 4 and 11, each strip 139 spans the opening 61 formed in the flue pipe 60. The baffle plate 136 is formed with upwardly extending legs 136a, the extremity of each leg bearing against the inner surface of the top wall 27 of the chamber 26. The baffle plate 136 may be held against displacement by drawing up on each of the nuts 139a. The plate 136 is provided with short fingers 140 extending into the furrows 34 formed by the corrugations in the front and rear walls 29 and 30, and is provided also with longer fingers 141 extending into the furrows 32 formed by the corrugated side walls 31. The space between the marginal surface of the fingers 140 and the adjacent surfaces defining the furrows 34 is somewhat less than the space between the fingers 141 and the adjacent surfaces defining the furrows 32, so as to restrict the passage of the products of combustion along the walls 29 and 30 adjacent the baffle 136, and encourage the passage of the products of combustion along the walls 31 adjacent the baffle 136.

It will be noted by inspection of Figures 4, 5,

and 6, that the flame issuing from the mouths 90a and 91a of the burners 90 and 91 is directed by the baffle means 94 and 95 toward the furrows 32 formed in the side walls 31.

5 Referring to Figures 10 and 11 there is shown a humidifying device 142 for further conditioning the air within the inner casing 16 and the bonnet chamber 24a, this humidifying device 142 comprising a pair of sheet-metal supporting plates 143 hinged together at one end as at 144, and each having a trough 145 formed at its other end. Each trough 145 is provided with a water outlet 146 leading to a suitable drain (not shown). The side marginal surfaces 15 of each supporting plate are extended and bend back upon the supporting plate to form guide-ways 147 between which is guided the side surfaces of a plate 148, the lower end of each plate terminating adjacent the bottom of a respective 20 trough 145, and the upper end having margins inclining upwardly toward the central part of the plate, as shown at 149, a recess 150 being formed at the junction of the inclined margins 149. The plate 148 is formed of material having 25 at least some absorbent characteristics, while at the same time having heat resistant characteristics, and one material found suitable for this purpose is asbestos. The plate 148 is provided with a plurality of apertures 151 for the 30 purpose of permitting heat to escape from the supporting plates 143. As shown in Figure 11, the humidifying device 142 straddles the flue pipe 60, and detachable connections 152 may be used for holding the humidifier device in 35 position with respect to the chamber 26.

A collecting cup 153, having a pair of nipples 154, is positioned above the humidifier device 142, so that the nipples are directly in line with the respective recesses 150 formed in the plates 148. As shown in Figure 10, the cup 153 is supported on a tube 155, leading exteriorly of the bonnet chamber 24a, and through a bracket 156, the tube 155 communicating with a cup 157 positioned directly beneath an outlet aperture in a valve 158. The valve 158 is connected to a source 40 of water supply by means of a tube 159, and the amount of water dripping into the cup 157 may be regulated by a manual adjustment 160. A thermostat 161 extends into the bonnet chamber 24a and is influenced by the temperature 45 within the bonnet chamber 24a, to automatically control the outlet aperture of the valve 158. The troughs 145 of the humidifier device 142 may have readily disconnectable connections with the drain conduits 146, so that the device 50 142 may be removed from the chamber 26, and because of the hinged joint, the legs 143 may be folded together, so that the entire device can be withdrawn from the bonnet chamber 24a through an opening such as for a riser 25.

60 A switch housing 162 is disposed within the compartment 19 formed by the outer casing 15, and contains switching devices 163 and 164, these devices being operated by a thermostat 165 leading into the bonnet chamber 24a, and 65 disposed along one side of the humidifying device 142. The switches 163 and 164 may be of the mercury type, the switch 163 controlling operation of the blower mechanism 52, and the switch 164 being connected to the motor device 110.

To operate the apparatus hereinbefore described, the switches 163 and 164 contained in the switch housing 162 are adjusted to operate at predetermined temperatures. The reset buttons 131 of the control devices 124 are pushed setting, the thermostat 165 will energize the

inwardly of the device casing so as to separate the bridges 129 from the contacts 130, and the pilot burners 116 and 117 are manually lighted, lighting of these pilot burners also providing a flame at the small apertures, such as the aperture 117a. After a sufficient interval, current will be generated by the thermo-electric junction 125 to energize the magnet 126 so as to hold the bridge 129 out of engagement with the contacts 130. When the bridge 129 is moved from engagement with the contacts 130, electrical connection of the control devices 124 with the motor device 110 is such as to effect movement of the motor device to open communication between the ports 102 and 104 of the valve 103, thus 15 supplying the burners 90 and 91 with gas, and this gas is ignited by the pilot burners 116 and 117. Of course, the motor device 110 simultaneously opens the doors 76 and 78 of the vestibules 73 and 74 so as to supply primary and 20 secondary air to the burner construction 81. The heat and products of combustion issuing from the burner conduits 90a and 91a will be directed by the baffles 94 and 95 into the furrows 32 formed by the corrugated side walls 31, the 25 products of combustion generally following the furrows 32, and being further urged toward the surfaces defining these furrows by the fingers 141 of the baffle 136. Some of the products of combustion will move toward the central part 30 of the chamber 26, and also run upwardly along the furrows 34 formed by the corrugated front and rear walls respectively, but because of the choking-off action produced by the fingers 140 of the baffle 136, the majority of the products 35 of combustion will pass along the furrows 32 and outwardly of the chamber 26, through the flue pipe 60.

After the temperature in the bonnet chamber 24a reaches a predetermined amount, the thermostat 165 will actuate the switch 163 so as to energize the motor 53, and cause operation of the blower mechanism 52. Air will be drawn into the blower chamber 56 through the conduit 57 and pass through the filtering means 58, this air entering the inlet of the blower mechanism and being expelled from the outlet of this mechanism into the compartment 48. The inclined wall 49 of the compartment 48 serves to direct the air upwardly through the exterior furrows 33 formed on the side walls 31, and the exterior 45 furrows 35 formed in the front and rear walls 29 and 30, as shown by the arrows in Figures 1 and 9. Figure 9 also shows, by means of arrows, the air passing around the lateral extension 38 and being directed toward the furrows 35 in the front wall 29 by means of the tubular members 41. Inasmuch as the air is confined to within the inner casing 16, air will also be forced upwardly along the elongated passage-ways 42 and 44 formed by the tubular members 41 and 43 50 and the adjacent surfaces of the walls 29, 30, and 31.

It will be obvious then that the heated products of combustion will be directed along the interior furrows 32 and 34, while the air to be heated is directed along the exterior furrows 33 and 35, and because of the large surface presented by the corrugated walls, a rapid exchange of heat is effected. The air is blown upwardly into the bonnet chamber 24a, and from there outwardly through the risers 25 to the rooms to be heated. Should the blower be powerful enough to lower the temperature in the bonnet chamber 24a to a predetermined low setting, the thermostat 165 will energize the

switch 163 to stop operation of the blower until a proper temperature may again be built up in the bonnet chamber 24a. On the other hand, if the temperature in the bonnet chamber 24a reaches a predetermined high value, the thermostat 165 will effect operation of the switch 164 so as to cause movement of the motor device 110 to close communication between the ports 102 and 104 of the valve 103, and also close the doors 76 and 78, until the temperature in the bonnet chamber 24a falls below the predetermined high setting.

The operation of the valve 158 controlling the water supply to the humidifier 142 is also controlled by the temperature in the bonnet 24a, a low temperature in this chamber causing restriction of the water supply to the humidifier, while a high temperature in the bonnet 24a causes more water to flow to the humidifier 142. It will be seen that as water drops from the nipples 154 of the cup 153 into the recesses 150 formed in the plates 148, this water will flow along the inclined surfaces 149 and over the edges of the surfaces 149 and recesses 150, and then gravitate over the outer surface of the plates 148. Some water will also be drawn upwardly of each plate 148 from the troughs 145 by capillary action. Heat within the bonnet chamber 24a, and heat supplied by radiation from the flue pipe 60 and the chamber 26 is sufficient to cause vaporization of the water gravitating over the surface of the plates 148, this heat being further distributed throughout the area of the plates 148 by reason of the apertures 151 formed in these plates.

A thermostat 166 may be placed in a room remote from the apparatus, and may be so connected to the motor device 110 so that if the room is not at the desired temperature, the device 110 will be energized to cause a supply of gas and air to flow to the burners. Of course, it will be apparent that the motor device 110 is also always under control of the switch 164 and the control device 124.

Referring to Figure 7, it will be noted that the corrugated construction of the walls 29, 30, and 31 provides for lateral expansion of the chamber 26, this expansion being taken up mostly by the corrugations, so that little expanding force is transmitted to the interior chamber 16, thus doing away with the objectionable "cracking" usually heard when the apparatus heats or cools. Also, because the chamber 26 is supported only on the flange 46 of the compartment 48, longitudinal expansion may also take place without any objectionable cracking noise.

It has been found preferable to increase the depth of the corrugations of the side walls 31, and so construct and arrange the heating means that the greater amount of heat is delivered along these side walls, since these walls are usually free of doors, flues, or the like. It will be appreciated that the furnace herein shown has a greater heating capacity than one where the corrugations of all the side walls are even. The heating capacity of the furnace herein shown can be increased by increasing the extent of the side walls 31, and since the burners extend along the side walls, it is a comparatively simple matter to increase the heating effect by adding additional burners to the burner assembly.

From the foregoing it will be apparent to those skilled in the art that I have accomplished at least the principal object of my invention, and it also will be apparent to those skilled in the art

that the embodiment herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto.

I claim:

1. Air conditioning apparatus, comprising: means, forming a main chamber, and having a corrugated wall portion defining at least a part of said main chamber, said wall portion providing extending ridges and furrows; means within said main chamber, forming an auxiliary chamber; manifold means, for mixing fuel with primary air, said manifold means being disposed within said auxiliary chamber; burner means, connected to said manifold means, the burner opening of said burner means being disposed within said main chamber; means, providing for the supply of secondary air to said auxiliary chamber; and directing means, so positioned as to direct the products of combustion from said burner opening into the furrows of said wall portion, said directing means having conduit means, the lower end of which receives secondary air from said auxiliary chamber and the upper end of which terminates above said burner opening, to supply secondary air to the rising products of combustion.

2. Air conditioning apparatus, comprising: means forming a chamber of generally polygonal cross-section, the wall portions defining said chamber being corrugated, providing longitudinally extending interior and exterior furrows and ridges, and adjacent wall portions at the corners of said chamber being so joined as to form a furrow at each corner, each of said corner furrows being defined by sides inclined with respect to each other an amount greater than the inclination of the sides defining the furrows intermediate the corner furrows; casing means, circumscribing the exterior ridges of said wall portions, forming spaces with the exterior intermediate furrows through which a fluid to be heated may be circulated, said casing means at the corners of said chamber being formed to follow the sides defining the corner furrows, but being spaced from these sides so that a fluid to be heated may be circulated therethrough, said spacing being of a predetermined amount so that fluid flow is distributed about the exterior of said chamber.

3. Air conditioning apparatus, comprising: means forming a chamber of generally polygonal cross-section, the wall portions defining said chamber being corrugated, providing longitudinally extending furrows and ridges, and adjacent wall portions at the corners of said chamber being joined; a casing, polygonal in cross-section, circumscribing the exterior ridges of said wall portions, forming spaces with the exterior furrows through which a fluid to be heated may be circulated, said casing at the corners of said chamber providing additional spaces through which a fluid to be heated may be circulated, each of said additional spaces being greater in cross-sectional size than the cross-sectional size of a space provided by any one of said exterior furrows; and means, within said additional spaces, so constructed and arranged to reduce the cross-sectional size of these spaces, so that fluid flow is distributed about the exterior of said chamber.

4. Air conditioning apparatus, comprising: means forming a chamber of generally polygonal cross-section, the wall portions defining said chamber being corrugated, providing longitudinally extending furrows and ridges, and adjacent wall portions at the corners of said chamber means being joined; a casing polygonal in cross-section, circumscribing the exterior ridges of said wall portions, forming spaces with the exterior furrows through which a fluid to be heated may be circulated, said casing at the corners of said chamber providing additional spaces through which a fluid to be heated may be circulated, each of said additional spaces being greater in cross-sectional size than the cross-sectional size of a space provided by any one of said exterior furrows; and hollow members positioned within said additional spaces, so constructed and arranged to reduce the cross-sectional size of said additional spaces and to provide for fluid flow along the adjacent surfaces of said chamber, so that fluid flow is distributed about the exterior of said chamber means.

5. Air conditioning apparatus, comprising: means forming a main chamber; means within said main chamber, forming an auxiliary chamber; manifold means, for mixing fuel with primary air, said manifold means being disposed within said auxiliary chamber; burner means, connected to said manifold means, the burner opening of said burner means being disposed within said main chamber; means, providing for the supply of secondary air to said auxiliary chamber; and deflecting means, so positioned as to direct the products of combustion from said burner opening, said deflecting means being hollow and the lower end receiving secondary air from said auxiliary chamber, and the upper end of said deflecting means terminating above said burner opening, to supply secondary air to the rising products of combustion.

6. Air conditioning apparatus, comprising: means forming a heating chamber; manifold means for mixing fuel with primary air; burner means connected to said manifold means and deflecting means positioned adjacent said burner means, directing products of combustion from said burner means against the peripheral wall of said chamber, said burner means and said deflecting means being so constructed and arranged that given parts of said peripheral wall are heated a greater amount than certain other parts, and said given parts being of greater area per unit of peripheral extent, said deflecting means having passage means constructed and arranged to provide for passage of secondary air, said passage means terminating adjacent said peripheral wall opposite said given parts.

7. Air conditioning apparatus, comprising: a generally rectangular sheet-metal receptacle, forming a heating chamber; manifold means for mixing fuel with primary air; a pair of burners extending along opposite walls of said receptacle, each burner being connected to said manifold means; and deflecting means positioned adjacent each of said burners directing products of combustion from said burners against respec-

tive ones of said opposite walls so that said opposite walls are heated a greater amount than the other opposite walls, and said opposite walls being of greater area per unit of peripheral extent than said other opposite walls, each of said deflecting means being hollow to form a passageway, one end of said passageway communicating with a source of secondary air and the other end terminating above a respective burner and adjacent a respective one of said opposite walls, to supply secondary air to the products of combustion rising along said respective wall.

8. Air conditioning apparatus, comprising: a sheet-metal receptacle forming a heating chamber, said receptacle being generally polygonal in cross-section, and each of the walls of said receptacle being of corrugated construction, the corrugations extending generally upright, and the corrugations of certain of said walls being deeper than the corrugations of the other walls so as to form deeper interior and exterior furrows; means for heating the interior of said chamber including burner means extending along said certain of said walls and means for directing heated matter from said burner means into the lower end of the deeper interior furrows; and baffle means spaced upwardly from said heating means and spaced downwardly from the upper end and the exhaust opening of said heating chamber, said baffle means extending unbroken across said heating chamber, and having marginal surfaces forming spaces with the adjacent surfaces of said walls, said marginal surfaces and said walls being relatively so constructed and arranged that a larger space is formed at said certain of said walls, so that a greater amount of heated matter is encouraged to flow along the upper end of said deeper interior furrows.

9. Air conditioning apparatus, comprising: a generally rectangular sheet-metal receptacle forming a heating chamber, each of the walls of said receptacle being of corrugated construction, the corrugations of two opposite walls being deeper than the corrugations of the other two walls; means for heating the interior of said chamber including burner means respectively extending along said two opposite walls transversely to the corrugations formed therein so that heat is delivered in a greater amount along said two opposite walls; and baffle means constructed and arranged to direct heated matter within said chamber toward the walls of said receptacle before such heated matter is exhausted from said heating chamber, said baffle means having finger means extending into each of the interior furrows formed in the walls of said receptacle but stopping short of contact with the adjacent surface of respective furrows to provide a space through which heated matter may flow, the finger means in the deeper interior furrows being constructed and arranged to provide a greater space than the finger means in the other interior furrows to encourage flow of a greater amount of heat along the surfaces defining said deeper interior furrows.

CHARLES L. BRYANT.
